CLAIM

The ornamental design for a foot pad exerciser, as shown and described.

DESCRIPTION

FIG. 1 is an isometric view of a foot pad exerciser showing my new design from the top and one side;

FIG. 2 is an isometric view thereof shown from the bottom and opposite end;

FIG. 3 is an isometric view of a second embodiment of the foot pad exerciser showing my new design from the top and one side; and,

FIG. 4 is an isometric view thereof shown from the bottom and opposite end.
